HEEL SEAT FITTING MACHINE

Ralph S. Megathlin, Quincy, Mass., assignor to
United Shoe Machinery Corporation, Flemington, N. J., a corporation of New Jersey

Application July 29, 1944, Serial No. 547,149

8 Claims. (Cl. 12—31.5)

This invention relates to heel seat fitting machines for use in the manufacture of shoes and is illustrated as embodied in an improved heel gage for use in such machines.

When the attaching faces of Cuban heels, the breasts of which have a substantial amount of front rake, are measured lengthwise in heel measuring gages of the general type disclosed in Figs. 1 to 7 of United States Letters Patent No. 2,053,295, granted September 8, 1936, on an application filed in the name of Fred L. MacKenzie, there is a tendency for the breast of the heel being measured to slide up an opposed face of a fixed heel breast engaging plate or bar of the gage as pressure is applied against the rear end of the heel by a sliding block of the gage, with the result that the heels "jump" out of the gage. Moreover, it has been found that heels having attaching faces of the same length but breasts of different angles of front rake, when measured in the gage disclosed in said patent, show widely different readings, largely due to the fact that the fixed heel breast engaging bar has considerable height and engages the breasts of the heels along lines spaced considerable distances from the attaching faces of the heels, the positions of said lines along the heel breasts varying in accordance with the angle of front rake of said breasts.

In order to insure against the heel jumping out of the gage, as above described, preparatory to or during the fitting of the outsole of the shoe for the reception of the heel, holdowns, such, for example, as shown in Fig. 8 of said patent, have been proposed. It has been found, however, that the heel seat fitting machine operators, who are usually on piece work, fail to use such holdowns because their use slows up the heel seat fitting operation.

It is an object of the present invention to provide, in a heel seat fitting machine, an improved heel gage in which heels, the breasts of which have different angles of front rake, may be quickly and effectively positioned and may be measured lengthwise with sufficient accuracy.

With the above object in view and in accordance with a feature of the present invention, the illustrative heel seat fitting machine is provided with a heel measuring gage comprising a support for a heel having, for example, a flat, forwardly raked breast, a bar fixed to the support and constructed and arranged to be engaged by the breast of the heel, a controlling unit comprising one or more members movable toward and away from the bar and constructed and

arranged to co-operate with the support and the bar in measuring the attaching face of the heel lengthwise, a heel holdown carried by but movable with relation to the controlling unit, and means for frictionally binding the holdown to said unit.

The fixed bar of the heel gage has a straight, serrated or otherwise roughened work engaging ridge which is arranged approximately $\frac{1}{16}$ of an inch above the heel support, which has the form of a table. The depth of the attaching face or cup of the heel is approximately $\frac{1}{8}$ of an inch, and it will be apparent that the ridge of the bar will be engaged by the upper lateral portions of the breast of the heel but not by the median portion of the heel breast. In the case of Cuban heels, the breasts of which are concave laterally, the bar will engage only the upper portions of the lateral breast edges of the heel. By providing a bar such as above disclosed, the only parts of the breast of the heel in engagement with the bar are those parts which in the finished shoe are in engagement with heel breast receiving shoulders formed on the outsole of the shoe. Accordingly, the serrations formed upon the ridge of the bar may be sharpened to such an extent that they penetrate the heel when the heel is forced against the fixed bar, it being immaterial whether or not portions of the breast of the heel in engagement with the bar are marked, since such portions are hidden in the finished shoe. By providing the bar with a sharp, serrated ridge, the tendency of heels, the breasts of which have considerable rake, to slide up over the bar is practically eliminated. Moreover, by arranging the heel breast engaging ridge of the fixed bar not more than $\frac{1}{16}$ of an inch above the heel engaging surface of the table, it has been found that the differences between the actual and the measured lengthwise dimensions of the attaching faces of heels having considerable front rake are negligible.

The illustrative holdown, which is pivoted to a sliding block of the movable controlling unit and is secured frictionally against free movement on said block, is quickly forced into engagement with the rear surface of the heel by the operator as he places the heel in the gage. It has been found that when the friction holdown is used with a one-piece controlling unit having the form of a sliding block, such, for example, as that illustrated in said Letters Patent No. 2,053,295, the operator sometimes fails to move the rear end of the rim of the attaching face of the heel against the movable block because of the presence of the friction holdown, with the result that a back

stop which positions the shoe in the machine, and is controlled by the said block, is improperly set. Because of the presence of the holdown, it is difficult for the operator readily to see whether or not the rear end of the rim of the attaching face of the heel has been moved into engagement with the block. Accordingly, the movable controlling unit of the illustrative gage comprises a slidable block, similar to the above-mentioned block disclosed in said patent, and an abutment which is pivoted to the block. When there is no heel in the gage, the abutment is swung to an idle or nongaging position away from a stop face of the block. In placing the heel in the gage, the rear end of the rim of the attaching face of the heel is brought into engagement with the abutment, which is swung upon the block under pressure of the heel until it engages said stop face of the block. In order that the operator can tell at a glance should the holdown prevent the rear end of the heel from being moved to its proper gaging position with relation to the slidable block, there are secured to the block and to the abutment upstanding indicators which are in alinement when the abutment has moved against the stop face of the block. When there is no heel in the heel measuring gage and the abutment is swung to its idle position away from the stop face of the block, the indicators are out of alinement.

By providing the above improved heel gage, Cuban heels, the breasts of which have different angles of front rake, can be quickly measured with sufficient accuracy without danger of the heel being displaced from the gage.

The various features of the invention will be understood and appreciated from the following description read in connection with the accompanying drawings, in which

Fig. 1 is a perspective view, partly broken away and partly in section, of a heel measuring gage and shoe positioning mechanism of the illustrative heel seat fitting machine;

Fig. 2 is a side view, partly in section, of the rear portion of the heel measuring gage, there being no heel in the gage;

Fig. 3 is a side view, partly broken away and partly in section, of said gage in the process of measuring a Cuban heel having a flat, forwardly raked breast;

Fig. 4 is a view on line IV—IV of Fig. 3, the positions of portions of a serrated ridge of a bar which is engaged by the breast of the heel being indicated by dot and dash lines;

Fig. 5 is an enlarged view showing in detail a portion of the serrated bar against which the breast of the heel is forced; and

Fig. 6 is a perspective view of the heel end of a finished shoe, the heel of the shoe being shown in dash lines.

The illustrative machine will be described with reference to measuring lengthwise the attaching face or cup 20 (Fig. 3) of a Cuban heel 22, which is to be attached to a shoe 24 (Figs. 1 and 6), preparatory to positioning the shoe lengthwise in the machine by a back gage 26 (Fig. 1). Except for hereinafter described improvements in the heel measuring gage, the illustrative machine is similar to the machine disclosed in United States Letters Patent No. 2,277,076, granted March 24, 1942, on an application filed in the name of William S. Dallas, said machine being an improvement upon the machine described in the above-mentioned Patent No. 2,053,295. Reference may be had to the above-mentioned patents for a full

understanding of the general construction and operation of the machine.

The heel measuring gage of the illustrative machine comprises a support having the form of a table 28 secured to the frame 29 of the machine and provided with a flat surface 30 constructed and arranged to be engaged by the rim 32 (Fig. 1) of the attaching face 20 of the heel which has a flat, forwardly raked breast 34 (Fig. 3). The attaching face 20 of the heel 22 is measured lengthwise between a fixed bar 36 constructed and arranged to be engaged by the breast 34 of the heel, and a controlling unit 38 which engages the rear end of the rim 32 of the attaching face 15 of the heel to set, through mechanism which will be hereinafter described, a rotatable spiral back stop 40. The controlling unit 38 comprises a slid- 20 able block 37 and a heel engaging abutment 39 (Figs. 2 and 3) which, for reasons appearing later, is pivotally connected to the block.

The bar 36 is fulcrumed upon a shouldered bearing pin 42 (Fig. 1) threaded into the machine frame 29 and is supported in the horizontal fixed position shown in Fig. 1 upon the table 28 with its inner end fitting in a notch 44 formed in an upstanding flange of the table. As above stated, the attaching face 20 of the heel 22 is measured lengthwise between the controlling unit 38 and the fixed bar 36 and, accordingly, it is desirable that the bar, which serves as an abutment for limiting forward movement of the heel, shall engage the forwardly raked heel breast 34 as close as practicable to the plane of the rim 32 of the attaching face of the heel, in order to minimize differences between the actual and the measured lengths of the attaching faces of various heels.

With the foregoing considerations in view, the bar 36 is provided with a straight, sharply serrated or otherwise roughened ridge 46 (Fig. 5) 40 which is engaged by the breast 34 of the heel and is positioned about $\frac{1}{8}$ of an inch above the surface 30 of the table 28. It will be apparent that in the above-described heel measuring gage heels which have attaching faces of the same length but have breasts of different forward rake will set the slidable controlling unit 38, and accordingly the spiral back stop 40, in slightly different operative positions. It has been found, however, that by engaging the breast 34 of the heel 22 not more than $\frac{1}{8}$ of an inch above the surface 30 of the table 28 any differences between the actual and the gaged lengthwise measurements of the attaching face of the heel are so small that they may be disregarded.

The cupped attaching faces of most heels have a depth of approximately $\frac{1}{8}$ of an inch and, accordingly, as best illustrated in Fig. 4, the upper corner portions of the flat breast of the heel are the only portions of the heel breast in engagement with the bar 36. Many Cuban heels have breasts which are concave laterally and it will be apparent that such heels will be engaged by the ridge 46 of the bar 36 only along their upper breast-edge portions. In the finished shoe the entire surface portions of the heel breast which have been in engagement with the bar 36 are in engagement with heel breast receiving shoulders 48 (Fig. 6) formed upon the outsole 50 of the shoe 24 and, accordingly, are not visible. If desirable, the ridge 46 of the bar 36 may be sharply serrated to penetrate the heel sufficiently to eliminate substantially the danger of the front ends of the heels, the breasts of which have considerable front rake, jumping out of the gage, as above explained.

The slidable controlling unit 38 is secured initially through a screw-and-slot connection 52 to a slide 54 movable forward and rearward in a guideway 56 (Fig. 1) of the table 28. The slide 54 is operatively connected through a coupling pin 58 to an upper arm 60 of a yoke 62 which is swiveled upon a fulcrum pin 64 secured by a screw 66 to the machine frame 29. A lower arm 68 of the yoke 62 is provided with teeth 70 meshing with teeth 72 of a small pinion 74 secured by a coupling pin 76 to the spiral back stop 40 and rotatably mounted upon the lower end of a vertical bearing stud 78 secured by a setscrew 80 to the machine frame 29. It will be apparent that the spiral back stop 40 may be swung into different angularly adjusted positions about the stud 78 in accordance with the position of the slidable controlling unit 38 and, accordingly, the length of the heel in the gage.

The slidable controlling unit 38 is constantly urged forward by a torsion spring 82 the lower end of which is attached to a stud 84 secured to a head of the pin 64 and the upper end of which is attached to a stud 86 secured to the yoke 62. Forward movement of the controlling unit 38 when there is no heel in the machine is limited by the engagement of a pin 88 mounted upon the back stop 40 with a pin (not shown) secured to the machine frame.

As fully disclosed in said Patent No. 2,277,076, rearward movement of the shoe in the machine is limited by engagement of a block 90, which is operatively connected to the back gage 26, with the spiral back stop 40. The shoe is positioned widthwise in the machine by a bifurcated centralizing gage 92 which is slidable together with and relatively to the back gage 26. When the heel-seat portion of the outsole 59 of the shoe 24 has been positioned in the machine, the margin of said heel-seat portion is forced against a beveled face 94 of a crease plate 96 by vertically movable clamps (not shown), the central part of the heel-seat portion of the outsole being forced through a U-shaped opening 98 of the crease plate while the margin of said heel-seat portion is clamped against the beveled face 94. Shoulder forming cutters 100 are then moved downward past forward edges 102 of the crease plate 96 to form the heel breast receiving shoulders 48 on the outsole 59 and a heel seat reducing cutter 104 is moved forward along a flat lower face of the crease plate into engagement with the shoulder forming cutters 100 to form a heel-seat tab 106 (Fig. 6) on the outsole, the outsole of the shoe being so trimmed that when the heel is properly positioned upon the shoe its upper breast corner portions, which have been engaged by the bar 36, will engage the heel breast receiving shoulders 48 formed on the outsole.

When heels, the breasts of which have considerable front rake, are forced against a high, frusto-conical surface of a front plate or bar of a heel gage such as illustrated in said Patent No. 2,053,295, or against a high, upstanding surface of a heel breast engaging bar of a gage such as illustrated in said Patent No. 2,277,076, there is a tendency, as above stated, for the heel, forced forward by a sliding block corresponding to the controlling unit 38, to ride up over the heel breast engaging bars, especially when there is considerable vibration in the machine. Moreover, as previously stated, such bars are objectionable because they engage the heel breast too far away from the plane of the rim of the attaching face of the heel and therefore cannot be used satis-

factorily as abutments in a gage for accurately measuring the lengths of the attaching faces of heels, the breasts of which have considerable front rake. By providing the bar 36 having the sharply serrated ridge 46 spaced $\frac{1}{6}$ of an inch from the surface 30 of the table 28, the attaching faces of heels, the breasts of which have different forward rakes, may be measured in the gage with sufficient accuracy. Moreover, the spring 82 may be strengthened so that the heel is forced against the sharp serrations of the ridge 46 of the bar 36 with pressure great enough substantially to eliminate the danger of the heel riding up over the bar.

In order, however, to insure against the heel being displaced in the gage, there is mounted upon a pin 108 carried by upstanding lugs 109 of the slidable block 37 a holddown 110 which may be quickly and effectively swung into engagement with the rear face of the heel by the operator as he places the heel in the gage. The holddown 110 is frictionally secured to the slidable block 37 by fiber pieces 112 (Fig. 2) which fit in bores 114 of the holddown and are forced with the desired amount of pressure against bosses of the upstanding lugs 109 of the block 37 by screws 116 threaded into the bores. It has been found that when the slidable one-piece block 37 with the friction holddown 110 is relied upon to force the heel against the fixed bar 36, said holddown is sometimes swung against the heel before the rim of the attaching face of the heel has been moved into engagement with the block, with the result that the heel is held away from the block by said holddown. In order to insure that the heel, when it is measured lengthwise in the gage, shall always assume the same position with relation to the slidable block 37, the controlling unit 38, in addition to the block 37, comprises the above-mentioned abutment 39 which is pivoted upon the pin 108 between the upstanding lugs 109 of the block 37. The abutment 39 is so constructed and is so supported upon the pin 108 that when there is no heel in the machine it moves to its idle position, shown in Fig. 2, away from a face 120 of the block, an end portion of a pin or indicator 122 secured to the abutment at such time being out of alignment with an end portion of a pin or indicator 124 secured to the block 37. When the rear end of the heel is forced against the abutment 39, said abutment, under pressure of the heel, swings into engagement with the face 120 of the block, assuming the position shown in Fig. 3, the end of the pin 122 of the abutment at such time being in alignment with the end of the pin 124 on the block 37. The pins 122 and 124 inform the operator at a glance when the abutment 39 is not in engagement with the face 120 of the block 37 and, accordingly, when the heel is not in its proper position with relation to the sliding block 37 of the controlling unit 38. In order to insure against the heel moving away from the table 28 under pressure of the abutment 39, a forward face 126 of said abutment extends forward over the rear end of the heel, the amount of forward overlap of said face increasing as the abutment is swung rearward into its operative gaging position, shown in Fig. 3.

Having described my invention, what I claim as new and desire to secure by Letters Patent of the United States is:

1. In a heel seat fitting machine, a heel gage for measuring the attaching face of a Cuban heel

75 lengthwise, said gage comprising a support con-

structed and arranged to be engaged by the rim of the attaching face of the heel, a bar having a ridge which is constructed and arranged to be engaged by the upper breast corner portions of the breast of the heel but not by other portions of the heel, said ridge being spaced from the support by a distance not greater than the height of heel breast receiving shoulders of a sole to be engaged in a finished shoe by the upper breast corner portions of the breast of the heel, and a member constructed and arranged to engage the rear end of the heel, said bar and said member being capable of relative approaching movement to measure the heel lengthwise.

2. In a heel seat fitting machine, a heel gage for measuring lengthwise the attaching face of a Cuban heel having a flat breast, said gage comprising a table constructed and arranged to be engaged by the rim of the attaching face of the heel, a fixed bar having a straight serrated ridge spaced from the table and constructed and arranged to be engaged by the upper corner portions of the breast of the heel but not by other portions of the heel, and a movable member constructed and arranged to engage the rear end of the rim of the attaching face of the heel and to force said heel against the ridge of the bar in order to measure the heel lengthwise.

3. In a heel seat fitting machine, a heel gage comprising a support for a heel, a fixed bar constructed and arranged to be engaged by the breast of the heel, a controlling unit movable toward and away from said fixed bar and constructed and arranged to co-operate with the support and the bar to measure the attaching face of the heel lengthwise, a holdown pivotally connected to the movable controlling unit, and means for frictionally binding the holdown to said unit, said holdown being movable against the rear end of the heel to force the latter against said bar to insure against movement of the front end of the heel away from said support.

4. In a heel seat fitting machine, a support for a heel, a fixed bar shaped and arranged to be engaged by the breast of the heel, a block movable toward and away from said bar, a holdown mounted for movement upon the block and held frictionally against free movement with relation to said block, an abutment which is pivoted to said block and has a portion constructed and arranged to be engaged by the rear end of the heel and to be swung by pressure of the heel into a gaging position against said block, an indicator secured to the block, and an indicator which is secured to the abutment and is aligned with the indicator on the block when said abutment is in its gaging position.

5. In a heel seat fitting machine, a heel measuring gage comprising a table constructed and arranged to be engaged by the rim of the attaching face of a heel, a fixed bar, a slidable block, a heel holdown which is pivotally connected to the block and which is frictionally bound to but movable under pressure with relation to said block, an abutment pivotally connected to the block and movable under pressure of the rear end of the heel to a gaging position in engagement with a face of said block, means for moving the block toward the fixed bar to cause the attaching

face of the heel to be measured lengthwise between the abutment and the bar, and indicators connected to the abutment and to the block respectively, said indicators being arranged in a predetermined conspicuous position when said abutment is in engagement with said face of the block.

6. In a heel seat fitting machine, a heel measuring gage comprising a table having a surface constructed and arranged to be engaged by the rim of the attaching face of a Cuban heel, a bar fixed to the table and having a serrated ridge which is spaced slightly from said surface of the table and is constructed and arranged to be engaged by the upper corner portions of the breast of the heel, a member slideable toward the bar to force the upper corner portions of the breast of the heel against said ridge of the bar and to co-operate with the bar and the table in measuring the attaching face of the heel lengthwise, a holdown pivoted to the movable member, and means for frictionally securing the holdown against free movement on said member, said holdown being movable against the rear face of the heel and being constructed and arranged to co-operate with the serrated ridge of the bar to insure against movement of the breast portion of the heel away from the table.

7. In a heel seat fitting machine, a heel measuring gage comprising a table having a flat surface constructed and arranged to be engaged by the rim of the attaching face of a Cuban heel, a fixed bar having a serrated ridge which is spaced slightly from the table and is constructed and arranged to be engaged by upper corner portions of the breast of the heel, a block constructed and arranged for movement along the table toward and away from said bar, a back stop for positioning lengthwise in the machine a shoe to which the heel is to be attached, connections between the back stop and the block, an abutment pivoted to the movable block and constructed and arranged to be engaged by the rear end of the rim of the attaching face of the heel and to be swung into a gaging position in engagement with an opposed face of said block, a holdown fulcrumed upon the block, means constructed and arranged frictionally to secure the holdown to the block but to permit the holdown to be moved against the rear end of the heel so as to cause the holdown to co-operate with said abutment and said bar in holding the heel in position upon the table, and indicators secured to the block and to the abutment respectively, said indicators being in alignment when the abutment is in engagement with said opposed face of the block.

8. In a heel seat fitting machine, a heel measuring gage, said gage comprising a support constructed and arranged to be engaged by the rim of the attaching face of a heel, a fixed bar having a ridge spaced from the support and constructed and arranged to be engaged by the upper corner portions of the breast of the heel but not by other portions of the heel, and a movable member constructed and arranged to engage the rear end of the rim of the attaching face of the heel and to force said heel against the ridge of the bar in order to measure the heel lengthwise.

RALPH S. MEGATHLIN.
